MECHANISM FOR TREATING FRESHLY
PRINTED WEBSChester Holsinger, Chicago, Ill., assignor to The
Goss Printing Press Company, Chicago, Ill., a.
corporation of Illinois

Application November 1, 1939, Serial No. 302,283

4 Claims. (Cl. 91—43)

The invention relates to new and useful improvements in printing and printing presses, and more particularly it relates to novel and useful improvements in means for treating freshly printed running webs to prevent offset and to improve the appearance of the product.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrate one embodiment of the invention, and together with the description, serve to explain the principles of the invention.

Of the drawing:

Fig. 1 is a sectional view, on line 1—1 of Fig. 2, of a mechanism embodying the invention; and

Fig. 2 is an enlarged transverse section on line 2—2 of Fig. 1.

The invention is directed to new and useful means for treating freshly-printed webs so as prevent offset, smutting, muddying of colors, or other marring of the work, and the invention finds useful application in color printing, where successive colors are superimposed, and also when oil inks are used in letter press printing on high speed webs, and the printed webs are thereafter handled in various ways, such as being associated, slit, collated, folded and the like. In addition to preserving the design from injury, the invention also enhances the quality and appearance of the work itself.

By my invention fast-running, freshly-printed webs are positively fed under tension, in a well-known manner, and the freshly-printed surfaces are treated or coated with very fine, non-metallic powder, as for example soapstone, talc, starch, flour, or other suitable substances. The opposite side of the web is supported at certain points, preferably by freely running rollers, and at the points where so supported the freshly-printed and coated surface is subjected to buffing action by a device or devices having an endless fabric surface. The fabric buffing surface is driven independently of the web driving means, thereby permitting practically any desired amount or degree of relative movement between the fast running web and the buffing surface. In much com-

mercial work I have found it advantageous and beneficial to run the buffing surface or surfaces at much higher speed than the web speed, and it is frequently advantageous to run the buffing surface at several times the web speed and in the opposite direction as the web. I have also found it advantageous to positively feed the web along a fairly direct or straight-away, though not necessarily a straight line, path, as contrasted with a sinusoidal or indirect and angular path.

It will be understood that the foregoing general description and the following detail description as well are exemplary and explanatory but are not restrictive of the invention.

Referring now in detail to the embodiment of the invention illustrated in Figs. 1 and 2, a freshly-printed web *w* is shown being fed under tension by suitable means, indicated conventionally by driven rolls or spaced apart discs 5 and 6, 15 and having other driving or guiding rolls or spaced apart discs 7 and 8, the web being fed under tension, as is customary, and along a fairly direct, generally convex path. The web *w* runs over a plurality of freely rotating supporting rollers 14, which engage and support the web on one side thereof. Cooperating with each of the supporting rollers 14 is a buffing roller 11, having a buffing surface, preferably of fabric, such as plush, flannel, knitted angora or other suitable yieldable material, which may be rotated at high speed without appreciable wear. Means are provided for regulating the pressure upon the web between each buffing roller and its supporting roller, to regulate the buffing action to a nicety, and as here shown each buffing roller is journaled in suitable adjustable eccentric bearings, indicated generally by 18. Means are provided for dusting or coating the freshly-printed web, and as shown, comprise a feeder having an elongated slotted discharge portion 21 for directing the powder onto, and entirely across, the web, and a suitable positive feed device 22 and a supply hopper 23.

Means are provided for driving the buffing surfaces independently of the web feed, and in accordance with one feature of the invention, the buffing surfaces may be driven at several times the web feed, and the buffing mechanism may be driven from the press or by an independent drive of its own. As here shown, the buffing rollers have on their shafts driving sheaves or pulleys 27, over which runs an endless belt 28, which belt also runs over a driving pulley 29. On the shaft of pulley 29 is a driven belt sheave 30, over which runs a belt 31 which also

runs over a pulley 32, driven by a motor 33. An enclosing housing 34 is preferably provided, and the rollers 14 may be provided with suitable cleaning devices such as scrapers 35.

In the buffing operation, the superfluous powder is removed from the web, and the web so treated has a polished or glazed appearance, which not only improves the quality of the appearance of the printed page itself, but also has an effect on the printed matter itself in a contrast relationship. In other words, the method of applying powder and thereafter buffing the same at high speed improves not only the quality of the printed matter, but gives the paper web so treated a finer appearance, as though the web was super-calendered. A web treated in this manner is able to pass through the folding angle bar, drive roller arrangement, cut-off arrangement, folding arrangement, and delivery arrangement without any offset in the signatures, either to the folder mechanisms or in the signatures as they are piled up in the delivery.

The invention in its broader aspects is not limited to the specific mechanisms shown and described but departures may be made therefrom within the scope of the accompanying claims without departing from the principles of the invention and without sacrificing its chief advantages.

What I claim is:

1. A mechanism for treating freshly-printed running webs, including in combination, means for positively feeding a running, freshly-printed web under tension in a generally downward direction, a plurality of freely rotating rollers located along and engaging the inner surface of said web and supporting and guiding the web in a convex path with its freshly printed side outermost, means for depositing powdered absorbent material on an outer freshly-printed surface of the running web, a plurality of buffing rollers engaging the outer powdered side of the printed web and arranged in pairs with said guiding rollers, to press the web between them, means for rotating said buffing rollers at a high speed relative to the web, and means for regulating the pressure between each buffing roller and its guide roller.

2. A mechanism for treating freshly-printed running webs, including in combination, means for positively feeding a running, freshly-printed

web under tension in a generally downward direction, a plurality of freely rotating rollers located along and supporting the inner surface of said web and supporting and guiding the web in a convex path with its freshly printed side outermost, means for depositing powdered absorbent material on the outward freshly-printed surface of the web, a plurality of buffing rollers engaging the outer powdered side of the printed web and arranged in pairs with said guiding rollers, the web being pressed between but not passing around a buffing roller and its supporting roller, means for rotating said buffing rollers independently of the web feed, and means for regulating the pressure between each buffing roller and its guide roller.

3. A mechanism for treating freshly-printed running webs, including in combination, means for directing a running freshly-printed web under tension in a generally downward direction, a plurality of freely rotating rollers located along and engaging the inner surface of said web and supporting and guiding the web in a convex path with its freshly printed side outermost, means for depositing powdered absorbent material on the outward freshly-printed surface of the web, a plurality of buffing rollers engaging the outer powdered side of the printed web and arranged in pairs with said guiding rollers, to press the web between them, means for rotating said buffing rollers independently of the web feed, and means for regulating the pressure between each buffing roller and its guide roller.

4. A mechanism for treating freshly-printed running webs, including in combination, means for positively feeding a running freshly-printed web under tension in a generally downward direction, a plurality of freely rotating rollers located along and engaging the inner surface of said web and supporting and guiding the web in a convex path with its freshly printed side outermost, means for depositing powdered absorbent material on the outward freshly-printed surface of the web, a plurality of buffing rollers engaging the outer powdered side of the printed web and arranged in pairs with said guiding rollers, to press the web between them, and means for rotating said buffing rollers independently of the web feed.

CHESTER HOLSINGER.
